UNITED STATES PATENT OFFICE

159,798

JAR FOR DISPENSING GROUND COFFEE

Harry C. Gessler, Brooklyn, N. Y., assignor to Medeo Products Co. Inc., North Bergen, N. J., a corporation of New Jersey

Application May 3, 1949, Serial No. 2,398

Term of patent 14 years

(Cl. D58—25)

To all whom it may concern:

Be it known that I, Harry C. Gessler, a citizen of the United States, and resident of Brooklyn in the county of Kings, State of New York, have invented a new, original, and ornamental Design for a Jar for Dispensing Ground Coffee, of which the following is a specification, reference being had to the accompanying drawing, forming a part thereof, and of which

Figs. 1 and 2 are, respectively, front and side elevational views of a jar for dispensing ground coffee showing my new design, and

Fig. 3 is a top plan view of the jar for dispensing ground coffee shown in Fig. 1.

I claim:

The ornamental design for a jar for dispensing ground coffee, substantially as shown.

HARRY C. GESSLER,
